UNITED STATES PATENT OFFICE.

EBENEZER B. BEECHER, OF WESTVILLE, CONNECTICUT.

IMPROVEMENT IN PAPER-BOX MACHINES.

Specification forming part of Letters Patent No. 148,653, dated March 17, 1874; application filed February 7, 1874.

To all whom it may concern:

Be it known that I, EBENEZER B. BEECHER, of Westville, in the county of New Haven and State of Connecticut, have invented a new and useful Improvement in Paper-Box Machines; and I do hereby declare that the following is a full and exact description of the same, reference being had to the accompanying drawings and to the letters of reference marked thereon.

This invention is especially designed for making blanks for match-boxes, the same being formed from a continuous strip of paper, which, in passing through the machine, is suitably scored and cut into proper form; and its novelty consists mainly in the employment of certain auxiliary rollers of peculiar construction, for the purpose of forcibly separating from the uncut end of the strip held by the scoring and cutting rollers the cut portions which have been imperfectly severed by the knives, thus insuring the perfect and complete separation of the parts, as will be fully described hereinafter.

In the drawings, Figure 1 represents a perspective view of the entire machine; Fig. 2, a central sectional elevation; Fig. 3, the manner of cutting the strip; Fig. 4, a perspective view of the blank, and Fig. 5 an elevation of the cutting and scoring roller.

To enable others skilled in the art to make and use my invention, I will now proceed to describe fully its construction and manner of operation.

A represents any suitable frame-work adapted to support properly the moving parts of the mechanism. b represents the shaft, to which the main power is applied in any suitable manner. It is supported in proper boxes in the frame-work, and is provided at one end with the gear-wheels b^1 b^2 , the first of which, b^1 , engages with the similar gear-wheel c^1 upon the corresponding end of shaft c , and the second with the gear-wheel d^1 upon the end of shaft d . The shaft b is provided with a cylindrical roller, B, and the shaft c with central segmental projections c^2 and the end projections c^3 c^4 , as shown. This shaft rests in proper boxes vertically adjustable in the guideways of the frame-work, and held in place by the coiled springs c^4 c^4 , which are themselves held

in position by studs c^5 c^5 , projecting from the securing-bar c^6 , as shown. By means of these springs the upper roller is permitted to yield vertically if a substance of unusual thickness passes between the rollers. D represents the pressure-roller, against which the knives act in cutting. It receives motion through its gear-wheel d^1 from the gear-wheel b^2 , and itself communicates motion by means of its gear-wheel d^2 , Fig. 2, to the corresponding wheel e^2 upon the shaft e . E represents the roller, provided with the scoring and cutting knives. These are suitably arranged, as indicated in Fig. 5, to make proper indentations upon the folding lines, and to separate the parts upon the lines to be cut. The roller D rests upon the roller E, and presses the pasteboard against the knives, this pressure being regulated by means of adjusting-screws in the bar, as shown.

It will be observed that the circumference of the gear-wheel b^2 is one-third of that of the gear-wheel d^1 , with which it engages, and consequently it will be understood the shaft b , and also the shaft c , which move with it, have a speed three times more rapid than the shafts d and e , which move together.

The operation is as follows: The machine having been put in motion, one end of a strip of pasteboard of proper width is introduced into the machine between the cutting and the pressing roller. The action of these rollers draws in the pasteboard, scores and cuts it, and delivers the blanks thus made, and the waste portions upon the other side. The knives upon the cutting-roller are themselves adapted in form to cut the complete blank; but in practice it is found impossible for any length of time to make them cut out perfectly the corners, so that the waste portions will not adhere thereto. To remedy this difficulty I employ the auxiliary rollers described, which operate in the following manner: The end of the strip having passed between the cutting and pressing rollers, then passes through between the auxiliary rollers b c before the blank is severed from the strip. It is not, however, acted upon by these rollers, as the two are not in contact until the blank is completely severed from the strip, as far as the knives can accomplish this result, at which time the central segmental projection of the roller c

reaches the pasteboard in its revolution, and, in connection with the lower roller, clamps the still adhering blank, and by means of the increased velocity of the rollers, the same is forcibly separated from that part still held by the more slowly-moving cutting-rollers. When the blank has been thus separated from the end of the strip, the waste portions *x* will be left projecting, as shown in Fig. 3, their rear sides still uncut and attached to the strip. As soon, however, as these parts are severed from the strip by the continued revolution of the cutting-rollers, they are seized in a similar manner by the end projections of the roller *c*, and forcibly separated from the other part.

The central segmental projection, it will be observed, has that edge which, in its revolution, strikes the pasteboard, beveled or inclined, so that no injury is done by its rapid movement.

The parts of the machine are, of course, adapted to work in harmony with each other.

The clamping-rollers take the blank and waste portions only after they have been cut from the strip, and the cutting-rollers are adapted to cut a blank at each of the revolutions of the clamping-rollers.

By means of the adjustment described, the pressure of the upper roller, relative to the knives, can be regulated at will, and the clamping-rollers are adapted to act with an elastic pressure.

The machine as a whole is quite simple in

its construction, and yet very effective for the purpose for which it is designed.

Having thus fully described my invention, what I claim as new, and desire to secure by Letters Patent, is—

1. The combination of the cutting-rollers *D* *E* with the auxiliary rollers *b* *c*, adapted by segmental projections and a more rapid revolution to clamp at intervals the blank and waste portions and separate them from the strip, substantially as described.

2. The roller *c*, provided with central segmental projection *c*² and the end segmental projections *c*³, relatively arranged as described, to clamp at proper intervals the blank and waste portions, as set forth.

3. In a machine for cutting box-blanks, the combination of the following elements: First, the cutting-rollers, adapted to draw in, cut, and deliver the strip; second, auxiliary rollers, adapted to receive the end of the strip and forcibly separate the same from the main part; third, the gearing connecting the two rollers, adapted to give a more rapid revolution to the auxiliary rollers than to the cutting-rollers, but having a certain fixed relation thereto, as described.

This specification signed and witnessed this 27th day of January, A. D. 1874.
